UNITED STATES PATENT OFFICE.

HERBERT E. MARKS, OF GLEN OSBORNE, PENNSYLVANIA.

ROOF OR FLOOR CONSTRUCTION.

Application filed April 14, 1922. Serial No. 552,489.

To all whom it may concern:

Be it known that I, HERBERT E. MARKS, a citizen of the United States, and a resident of Glen Osborne, Sewickley, in the county of Allegheny and State of Pennsylvania, have invented a new and useful Improvement in Roof or Floor Constructions, of which the following is a specification.

This invention relates to roof or floor constructions of the type in which cast slabs of cementitious material are supported on parallel spaced flanged bars or beams,—and in which metal mesh reinforcement or its equivalent is embedded in the cementitious slabs.

The object of the present invention is to increase the strength of such roof or floor constructions by locking together the reinforcing members at the contiguous ends of adjacent slabs to form a continuous reinforcement for the entire length of a panel of slabs.

Generally stated, the invention consists in having the reinforcements of the slabs project beyond their ends, and providing transverse metal members which interlock with such projecting portions and thus connect the reinforcement of adjacent slabs to form a continuous reinforcement.

In the accompanying drawings Fig. 1 is a plan view of a portion of a roof construction, partly broken away, showing one form of the invention; Fig. 2 is a longitudinal section on the line 2—2, Fig. 1; Fig. 3 shows one of the joints of Fig. 2 on an enlarged scale; Fig. 4 is a plan view showing in skeleton the joint of Fig. 3; Figs. 5, 6 and 7 are side views of three forms of interlocking members; Fig. 8 is a vertical longitudinal sectional view showing a modification of the joint; and Fig. 9 is a skeleton plan view of the same.

The drawings illustrate the invention applied to a roof construction, but it can be applied in an exactly similar way to a floor construction. In the drawings 1 represents the main beams of the structure, which in the case of a roof will be the purlins. 2 are flanged bars supported on the main beams or purlins, and spaced in parallelism and at distances apart equal to the width of the cementitious slabs. These bars are shown as T-bars having their legs extending upwardly and having laterally projecting flanges 4 at their bases. Any equivalent bars having lateral projecting flanges below

their upper edges will answer the same purpose.

5 indicates the cementitious slabs, which will be cast in now well known ways, of a width approximately equal to the distance between the flanged bars 2 and of any convenient or desired length. They are supported by the bars 2 by resting on the lateral projecting flanges 4 thereof.

These cementitious slabs have embedded therein a metal reinforcing fabric, which may be of any suitable construction but which is illustrated in the drawing as an open metal mesh comprising longitudinal or strand wires or rods 6 and cross or stay wires or rods 7, secured to the longitudinal wires or rods preferably by electrically welding the same thereto. The reinforcing fabric is of a length slightly greater than the length of the slabs so that the end portions thereof project beyond the ends of the slabs, and with one of the cross or stay rods spaced a predetermined and suitable distance from the end of the slab. These ends of the metal reinforcing fabric will project beyond the ends of the slab to such distances that when the slabs are placed in position, as shown in Fig. 3, said projecting ends will overlap. These projecting ends are locked together by a transverse bar or strip 8, provided with notches from one edge thereof spaced apart a distance equal to the spacing of the longitudinal members of the slab reinforcement, and into which notches the projecting ends of the said longitudinal members enter, with the transverse rod or wire 7 of the reinforcement lying beyond said interlocking bar or strip. That is to say, the transverse rod or wire 7 of the right hand slab in Fig. 3 lies on the left hand side of the interlocking bar or strip 8, while the transverse rod or wire 7 of the left hand slab lies at the right hand side of said interlocking bar or strip. Consequently the bar or strip 8 locks the reinforcement at contiguous ends of adjacent slabs together, so as to form a continuous reinforcement.

The strength of this continuous reinforcement is determined by the strength of the welds of the said rods 7 to the longitudinal rods 6. To increase this strength the longitudinal rods may be allowed to project slightly beyond the end transverse rods 7, and said projecting ends bent at right angles to the longitudinal bars, as shown at 9, Fig. 3; or the ends bent at right angles

can be used alone, that is, without the use of the transverse wires or rods 7 at the joints.

A single set of notches in the bars 8 will 5 accommodate both reinforcements, by having one lie above the other; or said notches may be of sufficient width to allow the two longitudinal rods to lie side by side, as shown in Fig. 4; or the notches may be 10 of inverted T, or L or like form, as shown in Figs. 5, 6, and 7; or two sets of closely adjacent notches may be provided in the bars 8, one set receiving the longitudinal rods of one slab and the other the longitudinal 15 rods of the other slab.

The interlocking bars or strips 8 may be thin flat strips of any kind. Preferably they will be of T form as shown, so that their lateral projecting flanges 10 form 20 supports for the ends of the slabs. The ends of these interlocking bars will rest upon the flanges 4 of the spaced bars 2, and in order to obviate a filling member on the flanges of the latter when the flanges of the 25 bars 8 are of material thickness, their bottom flanges may be coped off at their ends, as shown at 12, so that the flanges of said bars 8 will be in the same horizontal plane as the flanges of the bars 2.

30 Figs. 8 and 9 show a modification in which the ends of the longitudinal reinforcing rods 6^a are deformed laterally of their axes to form enlargements 13, with which the notched bars 8 interlock. In other respects 35 this will be applied in the same way as in the form already described. Any other way of forming or providing the longitudinal reinforcing rods with laterally projecting portions with which the notched bars 8 will 40 interlock, can be employed.

In laying a sloping roof, the slabs at the ridge of the roof will be first placed in 45 position and secured in place, and the slabs lower down will be successively placed in position and thus in a sense hung onto the upper slabs. In this way all slack is taken up and the reinforcement is put in initial 50 tension so that in the completed structure the reinforcement becomes effective as a tension member. In laying a flat roof or 55 floor, the initial tension can be secured by securing one slab in position, then laying the next slab in place, interlocking the ends of the projecting reinforcing fabric, and then moving the last laid slab longitudinally until all slack is taken up.

After the slabs are properly positioned 60 the gaps between contiguous ends of adjacent slabs are filled with grouting, as shown at 14, entirely closing said gaps and embedding the joint, and in effect forming a continuous cementitious slab.

65 The slabs 5 are provided on their under-surfaces with a finishing sheet of paper or like material, in order to give a finished

surface to the lower face of the roof structure, and also do away with the necessity of dusting off the slabs to remove loose particles. Such finishing surface can be readily provided by casting the slabs on 70 sheets of paper or like material laid into the slab molds. This feature, however, is not claimed in this application, but is claimed in an application of even date here- 75 with, Serial Number 552,490.

The slabs 5 may be provided with cored out openings or passages between their top surface and the metal reinforcement therein, in order to reduce their weight. Such openings will preferably extend in the direction 80 of the longitudinal or strand member 6 of the reinforcement, and are indicated by the dotted lines 16, Fig. 3. This feature is not claimed in this application but is claimed in the above identified application Serial 85 No. 552,490.

Manifestly in lieu of the purlins and parallel T-bars shown, various frame constructions may be used to support the slabs. Indeed, the slabs may be supported directly 90 by the main beams of the roof or floor structure, by spacing the main beams so as not to exceed the width or length of the slabs.

The roof or floor construction described is 95 simple, easy to erect, and gives maximum strength for the amount of material used. While the slabs are individually cast, the interlocking of the ends of the reinforcement of adjacent slabs provides a continuous 100 reinforcement from end to end of the panel.

I claim:

1. A roof or floor construction, comprising supporting bars, cementitious slabs resting on said bars, metal reinforcing members embedded in said slabs and projecting beyond the ends thereof, the extremities of the reinforcing members being bent laterally, the reinforcing members at contiguous ends of adjacent slabs overlapping, and 110 transverse metal members covering the gap between adjacent slabs and having a portion disposed directly within the space therebetween, said portion lying between the said bent extremities of adjacent slabs for interlocking the projecting ends of the reinforcement and thereby connecting the same to form a continuous reinforcement throughout the entire structure.

2. A roof or floor construction, comprising supporting bars, cementitious slabs resting on said bars, metal reinforcing members embedded in said slabs and projecting beyond the ends thereof, the extremities of the reinforcing members being bent laterally, the reinforcing members at contiguous ends of adjacent slabs overlapping, transverse metal members which overlap the ends of adjacent slabs covering the gap therebetween and having a portion disposed di- 120

- rectly within the space between the slabs, adjacent slabs, thereby connecting the individual reinforcements to form a continuous reinforcement.
5. A roof or floor construction comprising parallel bars having lateral flanges, cementitious slabs resting on said flanges, metal reinforcing fabric composed of cross and longitudinal members embedded in said slabs and having portions disposed beyond the ends at opposite sides thereof, transverse metal members provided with notches to interlock with the said ends of the said reinforcement at contiguous ends of adjacent slabs, thereby connecting the reinforcement of said slabs to form a continuous reinforcement, said transverse metal members resting at their ends on the flanges of the parallel bars and provided with bottom flanges extending underneath the ends of said slabs.
6. A roof or floor construction comprising supporting bars, cementitious slabs resting on said bars, a metal reinforcing fabric embedded in said slabs and having longitudinal members projecting beyond the ends thereof, said projecting ends being provided with portions extending transversely to the axes of said longitudinal members, and notched transverse members receiving said longitudinal reinforcing members and engaging the said transversely extending portions thereof, thereby connecting the longitudinal reinforcing members to form a continuous reinforcement.
7. A roof or floor construction comprising supporting bars, cementitious slabs resting on said bars, a metal reinforcing fabric embedded in said slabs and having longitudinal members projecting beyond the ends thereof, transverse members secured to the projecting ends of said longitudinal members, and means disposed between and abutting the contiguous faces of said transverse members of adjacent slabs whereby to connect the reinforcing fabric of said slabs and form a continuous reinforcement.
8. A roof or floor construction comprising supporting bars, cementitious slabs resting on said bars, a metal mesh reinforcing fabric composed of cross and longitudinal members embedded in said slabs and having portions disposed beyond the ends at opposite sides thereof, said portions including a cross member of said mesh, and notched strips extending transversely of the slabs and receiving the longitudinal members and engaging the cross members of the said portions of said fabric on contiguous ends of
10. 3. A roof or floor construction, comprising supporting bars, cementitious slabs resting on said bars, a metal reinforcing fabric embedded in said slabs and having longitudinal members projecting beyond the ends thereof, said projecting ends being provided with portions extending transversely to the axes of said longitudinal members, and notched transverse members receiving said longitudinal reinforcing members and engaging the said transversely extending portions thereof, thereby connecting the longitudinal reinforcing members to form a continuous reinforcement.
15. 4. A roof or floor construction comprising supporting bars, cementitious slabs resting on said bars, a metal reinforcing fabric embedded in said slabs and having longitudinal members projecting beyond the ends thereof, transverse members secured to the projecting ends of said longitudinal members, and means disposed between and abutting the contiguous faces of said transverse members of adjacent slabs whereby to connect the reinforcing fabric of said slabs and form a continuous reinforcement.
20. 5. A roof or floor construction comprising supporting bars, cementitious slabs resting on said bars, a metal mesh reinforcing fabric composed of cross and longitudinal members embedded in said slabs and having portions disposed beyond the ends at opposite sides thereof, said portions including a cross member of said mesh, and notched strips extending transversely of the slabs and receiving the longitudinal members and engaging the cross members of the said portions of said fabric on contiguous ends of
25. 6. A roof or floor construction comprising supporting bars, cementitious slabs resting on said bars, a metal mesh reinforcing fabric composed of cross and longitudinal members embedded in said slabs and having longitudinal members projecting beyond the ends thereof, transverse members secured to the projecting ends of said longitudinal members, and means disposed between and abutting the contiguous faces of said transverse members of adjacent slabs whereby to connect the reinforcing fabric of said slabs and form a continuous reinforcement.
30. 7. A roof or floor construction comprising supporting bars, cementitious slabs resting on said bars, a metal mesh reinforcing fabric composed of cross and longitudinal members embedded in said slabs and having longitudinal members projecting beyond the ends thereof, transverse members secured to the projecting ends of said longitudinal members, and means disposed between and abutting the contiguous faces of said transverse members of adjacent slabs whereby to connect the reinforcing fabric of said slabs and form a continuous reinforcement.
35. 8. A roof or floor construction comprising supporting bars, cementitious slabs resting on said bars, a metal mesh reinforcing fabric composed of cross and longitudinal members embedded in said slabs and having longitudinal members projecting beyond the ends thereof, transverse members secured to the projecting ends of said longitudinal members, and means disposed between and abutting the contiguous faces of said transverse members of adjacent slabs whereby to connect the reinforcing fabric of said slabs and form a continuous reinforcement.

In testimony whereof, I sign my name.

HERBERT E. MARKS.
